Fig. 4.

Fig. 5.

FIGURE 1 is a top plan view of a jewel showing my new design;

FIGURE 2 is an edge view looking in the direction of the cleft of the heart shape jewel of FIGURE 1;

FIGURE 3 is a side edge view thereof taken from the right side of FIGURE 1, the opposite edge being a mirror image thereof;

FIGURE 4 is an edge view thereof looking in the direction of the point; and

FIGURE 5 is a bottom plan view of FIGURE 1.

A characteristic feature of the ornamental design of the invention is the heart-shaped configuration of the girdle of the jewel when considered in combination with the particular arrangement of facets below the girdle and V-shaped grooves in the bottom of the jewel.

I claim:

The ornamental design for a jewel, substantially as shown and described.
